UNITED STATES PATENT OFFICE.

ROBERT F. DARBY, OF CHICAGO, ILLINOIS, ASSIGNOR TO AMERICAN STEEL FOUNDRIES, OF CHICAGO, ILLINOIS, A CORPORATION OF NEW JERSEY.

CAST-STEEL CARRY-IRON.

1,143,689.

Specification of Letters Patent. Patented June 22, 1915.

Application filed September 11, 1913. Serial No. 789,225.

To all whom it may concern:

Be it known that I, ROBERT F. DARBY, a citizen of the United States, residing at Chicago, in the county of Cook and State of Illinois, have invented certain new and useful Improvements in Cast-Steel Carry-Irons, of which the following is a specification.

My invention relates to railway draft mechanism and has particular reference to 10 a novel carry iron for supporting a car coupler in a car end sill.

It is well understood that car couplers are usually provided with a long shank which extends within the limits of the car and 15 abuts a shock absorbing device. The car coupler usually extends through a recess in the end sill and must therefore be supported in a suitable manner at the end sill. The recess in the end sill through which the coupler shank extends is usually made of a size greater than the coupler shank to permit 20 sidewise movement of the coupler as required as the cars are rounding curves. This necessitates a movement of the car coupler 25 and a consequent wear upon the supporting member. It is desirable that the wear should be taken up by the supporting member rather than the coupler shank inasmuch as the coupler should outwear the carry 30 iron. Therefore the carry iron should be of a softer metal than the coupler shank. However, if a carry iron is made of such 35 soft metal it does not provide the necessary rigidity and resistance to the shocks occasioned in service. I have conceived therefore, the idea of constructing a carry iron of cast steel whereby it may be made strong and rigid and providing for a wear plate which plate may be of softer metal and take 40 the wear incident to service. This wear plate may be of exceedingly simple construction whereby it may be replaced on any repair track.

The wearing of the coupler shank or its 45 supporting member causes the coupler to lower in its position with reference to the rail. Also the wear in service of the various parts of the truck, the permanent set of the springs and the change in the camber of 50 the car causes the coupler to lower in its position with reference to the rail. The lowering of the coupler must be compensated for by the raising of the coupler to keep it within the height prescribed by law.

55 A further object therefore is the provi-

sion for the easy adjustment of the height of the coupler during the service life of the car; 1st, by inserting a wearing plate of a different transverse thickness; 2nd, by inserting a liner underneath the wearing 60 plate which is in the carrier iron at the time the adjustment is made, thus changing the height of the wearing plate and the coupler; 3rd, by reversing a worn wearing plate and thus compensating for the change in 65 height due to the wear in the plate.

A further object is to provide a carry iron which may be readily inserted or removed when necessary.

The invention will be more readily understood by reference to the accompanying drawings, wherein,

Figure 1 is a plan view of my novel carry iron; Fig. 2 is an end view of the construction shown in Fig. 1; Fig. 3 is a vertical section on the line 3—3 of Fig. 2, and, Fig. 4 is a perspective view of the carry iron with the removable wear plate installed.

Referring more particularly to the drawings, it will be seen that the end sill or end plate 10, is provided with outwardly projecting apertured webs 13. These webs, together with supporting bolts, form the supports for the carry iron, which consists of a steel casting having rounded end portions 14, apertured at 15, and between the ends provided with a web 16, forming the floor thereof. This web is bounded on both sides by the downwardly extending flanges 17, and at its corners by the upwardly extending discontinuous flanges 18. Intermediate lugs 19, form stops for the removable wear plate 20. This plate is formed preferably of wrought iron or similar material and may be of various transverse thicknesses to adjust the height of the coupler as indicated in dotted lines in Fig. 2. The coupler may also be raised by inserting liner shown by dotted line 22, underneath the old wearing plate, causing the top of the latter to be raised to the dotted line position of Fig. 2. In any event, the plate acts as a wear and adjustment plate taking up the wear and preventing excessive wear either on the coupler shank or the carry iron and providing 100 easy means of adjusting the coupler to height. When worn it can easily be replaced or lined up or if worn on one side of the center can, if necessary, be reversed presenting a new face on the opposite side. As a 105 110

holding means I provide the bolts 21, passing through the carry iron and the webs 13. The form of connection at the ends of the carry iron may be changed to suit different conditions.

It is obvious that modifications may be made in the construction shown and such modifications as are within the scope of my claims I consider within the spirit of my invention.

I claim:

1. A carry iron comprising a body provided with terminal attaching ears offset above the top of the body, upstanding lugs at the front and also at the back of the body adjacent the inner sides of the attaching ears, and end lugs between the front and rear lugs, the inner face of each end lug being located back of the line of the inner faces of the adjacent front and rear lugs, the several lugs defining a seat for a wear plate.

2. A carry iron comprising a body provided with terminal attaching ears offset above the top of the body, upstanding lugs at the front and also at the back of the

body adjacent the inner sides of the attaching ears, end lugs between the front and rear lugs, the inner face of each end lug being located back of the line of the inner faces of the adjacent front and rear lugs, the several lugs defining a seat for a wear plate, and a wear plate in the seat and of a vertical thickness exceeding that of the lugs.

3. A carry iron comprising a plate body having a flat top, front and rear depending longitudinal flanges, terminal attaching ears offset above the top of the body and in a plane substantially parallel thereto, upstanding lugs at the front and also at the back of the body adjacent the inner sides of the attaching ears, and end lugs between the front and rear lugs, the inner face of each end lug being located back of the line of the inner faces of the adjacent front and rear lugs; the several lugs defining a seat for a wear plate.

ROBERT F. DARBY.
